UNITED STATES PATENT OFFICE.

PAULINE S. McOMBER, OF HASTINGS, MICHIGAN.

BRASSIÈRE.

1,267,432.

Specification of Letters Patent. Patented May 28, 1918.

Application filed March 28, 1918. Serial No. 225,152.

To all whom it may concern:

Be it known that I, PAULINE S. McOMBER, a citizen of the United States, residing at Hastings, county of Barry, State of Michigan, have invented certain new and useful Improvements in Brassières, of which the following is a specification.

This invention relates to improvements in brassières.

10 My improvements relate particularly to the fasteners for brassières or securing means of the class shown in my patent issued July 31, 1917, No. 1,235,218.

15 The object of this invention is to provide a fastening means for holding the front of brassières in proper position whether used with front or back lace corsets.

20 Further objects, and objects relating to structural details, will definitely appear from the detailed description to follow.

I accomplish the objects of my invention by the devices and means described in the following specification. The invention is clearly defined and pointed out in the claims.

25 A structure which is a preferred embodiment of my invention is clearly illustrated in the accompanying drawing, forming a part of this specification, in which:

Figure I is a detail front view of my improved device shown in connection with a front lace corset, only portions of the brassière and corset being shown.

30 Fig. II is a view similar to Fig. I showing my improved device in use with a back lace corset.

Fig. III is a front elevation of my improved fastening device.

Fig. IV is an edge view thereof.

40 Fig. V is an enlarged detail vertical section on a line corresponding to line 5—5 of Figs. I and III.

In the drawing similar reference characters refer to similar parts throughout the several views, and the sectional views are 45 taken looking in the direction of the little arrows at the ends of the section lines.

Referring to the drawing, 1 represents a corset of the front lace type over the upper end of which is adjusted a brassière 2 having 50 overlapping edges 3. To the bottom of one of these overlapping edges is secured a holding or retaining strap 4 which may be of any suitable material, preferably a tape, and may be either elastic or inelastic as desired.

55 My improved fastener device 5 is adjustable on this strap 4. The upper end of my

fastener device has a rearwardly turned lace engaging hook 6 and its lower end a key-hole stud engaging slot 7 adapted to be engaged with a stud, as 8, in a back lace corset,—see Fig. II. Intermediate the hook 6 and the stud slot 7 are transverse slots 9 and 10 adapted to receive the strap 4, the end of the strap being preferably passed forwardly through the lower slot 9 and upwardly and rearwardly through the upper slot 10 as illustrated. The upper edge of the lower slot is preferably provided with teeth 11. A tongue 12 projects upwardly and rearwardly from the lower edge of the upper slot 10. 70

When the hook 6 is engaged with a lace, as 13, the lace draws down until it is supported by the tongue 12 binding the strap thereon preventing the slipping of the strap, and this also prevents the forward tilting 75 of the fastener so that it is quite impossible for the lace to become accidentally disengaged. At the same time it may be quickly and easily engaged and disengaged and the fastener easily adjusted to the proper position on the strap.

From the above description it will be clear that my improvements may be used interchangeably with the back lace or front lace type of corset. 85

Having thus described my invention, what I claim as new and desire to secure by Letters Patent, is:

1. The combination with a brassière provided with a corset attaching strap, of a 90 fastener having spaced slots adapted to receive said strap, the lower end of said fastener being adapted to engage a corset stud, the upper end being provided with a hook adapted to engage a corset lace, the lower 95 edge of the upper strap slot having a rearwardly projecting tongue with which a corset lace engaged with said hook coacts to bind the strap and prevent the forward tilting of the fastener, the upper edge of the 100 lower slot having a strap engaging tooth thereon.

2. The combination with a brassière provided with a corset attaching strap, of a fastener having spaced slots adapted to receive said strap, the lower end of said fastener being adapted to engage a corset stud, the upper end being provided with a hook adapted to engage a corset lace, said fastener having an upwardly and rearwardly 105 projecting tongue with which a corset lace engaged with said hook coacts to bind the 110

strap and prevent the forward tilting of the fastener.

3. The combination with a brassière provided with a corset attaching strap, of a fastener having spaced slots adapted to receive said strap, the upper end of said fastener being adapted to engage a corset lace, said fastener having a tongue at the rear of the upper slot with which a corset lace engaged with said hook coacts to bind the strap and prevent the forward tilting of the fastener.

4. A fastener of the class described having spaced slots adapted to receive a strap, the lower edge of the upper slot having an upwardly projecting rearwardly inclined tongue so that a strap may be disposed through the lower slot and passed upwardly and rearwardly through the upper slot over said tongue and a lace engaged transversely between such strap and the body of the fastener above said tongue.

5. A fastener of the class described, having a key-hole stud engaging slot at its lower end and spaced transverse slots above said key-hole slot adapted to receive a strap, the lower edge of the upper strap slot having a

rearwardly inclined upwardly projecting tongue thereon, the upper edge of the lower slot having teeth thereon.

6. A fastener of the class described, having spaced transverse strap slots, there being a rearwardly projecting tongue on the lower edge of the upper slot adapted to support a lace disposed between a strap engaged with the strap slots and the body of the fastener, the upper edge of the lower slot being provided with strap engaging teeth.

7. A fastener of the class described, having a stud engaging slot at its lower end and spaced transverse strap slots above said stud slot, there being a rearwardly inclined tongue projecting upwardly at the rear of the upper strap slot adapted to support a lace disposed between a strap engaged with the strap slots and the body of the fastener.

In witness whereof, I have hereunto set my hand and seal in the presence of two witnesses.

PAULINE S. McOMBER. [L. S.]
